Primary Examiner — Karen E Kearney(74) *Attorney, Agent, or Firm* — Altera Law Group, LLC(57) **CLAIM**

The ornamental design for a USB drive, as shown and described.

DESCRIPTION

FIG. 1 is a perspective view of the USB drive.

FIG. 2 is a rear view thereof.

FIG. 3 is a front view thereof.

FIG. 4 is a side view thereof.

FIG. 5 is the other side view thereof.

FIG. 6 is a top view thereof.

FIG. 7 is a bottom view thereof.

FIG. 8 is a perspective view like FIG. 1 except with the tang in closed position thereof.

FIG. 9 is a bottom view like FIG. 2 except with the tang in closed position thereof; and,

FIG. 10 is a bottom view of the tang in closed position thereof. The broken line showings are included for the purpose of illustrating portions of the USB drive and form no part of the claimed design.
